UNITED STATES PATENT OFFICE.

GEORGE OTTO SCHNELLER, OF ANSONIA, CONNECTICUT.

IMPROVEMENT IN CORSET-SPRINGS.

Specification forming part of Letters Patent No. 123,938, dated February 20, 1872.

To all whom it may concern:

Be it known that I, GEORGE OTTO SCHNELLER, of Ansonia, in the county of New Haven and State of Connecticut, have invented a new and useful Improvement in Corset-Springs; and I do hereby declare the following to be a full, clear, and exact description thereof, which will enable those skilled in the art to make and use the same, reference being had to the accompanying drawing forming part of this specification, in which drawing—

Figure 1 represents a face view of my invention. Fig. 2 is a longitudinal section of the same in the plane xx , Fig. 1.

Similar letters indicate corresponding parts.

This invention relates to that class of corset-springs in which is employed a mainspring provided with an auxiliary leaf; and the invention consists in securing the secondary leaf upon the mainspring and by means of projecting teats or lugs located on each side of the central fastening-clasp, the ends of the said secondary leaf being loosely confined between the end clasps so as to accommodate itself to the motions of the main leaf.

In the drawing, the letter A designates a corset-spring, which is composed of a main-spring, *a*, and secondary leaf, *b*. The secondary or auxiliary leaf is slipped loosely through the fastening-clasps *c*, which are provided with recesses to receive the same; and it is held in position by two projections, *d d*, raised thereon, one on either side of the central clasp *c*.

By these means the secondary leaf is prevented from being displaced, and, at the same time, its ends are left free to accommodate itself to the motions of the mainspring, and the main-spring retains its full strength, there being no perforations for rivets. The mainspring and auxiliary leaf may be made of any desired material; but, by preference, the mainspring is made of highly-tempered steel, while the auxiliary leaf is made of some tough metal, such as hard rolled brass, which has a certain degree of elasticity, but which is not liable to break.

By combining the two leaves *a b* so that the leaf *b* will have its free ends arranged between clasps *a* a spring is produced which combines superior elasticity, and which will permit the said secondary spring to accommodate itself to the movement of the mainspring.

Having thus described my invention, what I claim as new, and desire to secure by Letters Patent, is—

As a new article of manufacture, the corset-spring, constructed as described, consisting of the mainspring *a*, auxiliary leaf *b*, projections *d d*, and clasps *c c*, all combined and operating as herein shown and set forth.

This specification signed this 8th day of January, 1872.

GEO. O. SCHNELLER.
